UNITED STATES PATENT OFFICE

JOSEPH P. RYAN, OF CHICAGO, ILLINOIS

DESIGN FOR A SIGN

Application filed March 19, 1931. Serial No. 39,148. Term of patent 7 years.

To all whom it may concern:

Be it known that I, JOSEPH P. RYAN, a citizen of the United States, residing at Chicago, in the county of Cook and State of Illinois, have invented a new, original, and ornamental Design for a Sign, of which the following is a specification, reference being had to the accompanying drawings forming part thereof.

I claim:

The ornamental design for a sign, as shown.

JOSEPH P. RYAN.
